UNITED STATES PATENT OFFICE.

WILLIAM D. ANTRIM, OF GLOUCESTER CITY, NEW JERSEY, ASSIGNOR TO WELSBACH COMPANY, OF GLOUCESTER, NEW JERSEY, A CORPORATION OF NEW JERSEY.

GAS-HEATER.

1,362,214.

Specification of Letters Patent. Patented Dec. 14, 1920.

Application filed September 18, 1919. Serial No. 324,543.

To all whom it may concern:

Be it known that I, WILLIAM D. ANTRIM, a citizen of the United States, residing at Gloucester City, in the county of Camden and State of New Jersey, have invented a new and useful Improvement in Gas-Heaters, of which the following is a full, clear, and exact description.

The present invention relates broadly to 10 gas heaters or radiators, and more particularly to a heater of this type having a plurality of heat radiating elements.

The principal object of the present invention is to provide a gas heater having a plurality of individual heating elements all of 15 which are held at one portion thereof in a common header.

Another object of the present invention is to provide a heater of the type described 20 in which each of the heating elements has an opening or openings formed adjacent the upper ends thereof, which ends are adapted to be received and maintained in position in a common header communicating with any 25 suitable form of pyrophoric or other lighting device.

The foregoing and other objects, together 30 with their attendant advantages, will be apparent as the invention becomes better understood by reference to the accompanying specification and drawings forming a part thereof, it being premised that changes may be made in the various details and the manner of operation within the scope of the 35 appended claims without departing from the spirit of the invention.

Figure 1 is a front elevation of my improved gas heater.

Fig. 2 is a longitudinal horizontal section 40 on the line II—II of Fig. 3.

Fig. 3 is a longitudinal section on the line III—III of Fig. 4, and

Fig. 4 is a transverse section on the line IV—IV of Fig. 2.

Referring more particularly to the drawings, the present gas heater is illustrated as of the portable type comprising a base 2 formed of suitable sheet or pressed metal supported on legs 4, adjacent the corners 50 thereof. The base plate is preferably formed with an upwardly and rearwardly extending portion 5 forming a common chamber adjacent the bottom of the heater

for the reception of a plurality of Bunsen burner tubes 6 communicating at their lower ends with a gas supply line 7 suitably supported beneath the base 2 of the heater. A back member 8 is held in position on the base by means of a suitable top 9 secured in position by the ornamental knobs 10. The top 9 in its preferred embodiment is constructed with a downwardly and rearwardly extending portion 11 corresponding generally to the base 2. The sides 12 of the heater may be formed integrally with the back and are preferably provided at their forward extremities with curved portions 14 having a longitudinally extending opening 15 left between the inecting edges thereof for the purpose hereinafter more specifically pointed out. Slidably received within the openings 15 is a curved heat-reflecting element 16 extending substantially the entire length and width of the heater. Coöperating with each of the burners 6 in front of the reflecting element 16 is a heat-radiating element 17 which may be of any desired configuration, but preferably formed with an opening or openings 18 adjacent the upper end thereof adapted to extend through suitable openings 19 formed in the downwardly and rearwardly extending portion 11 of the top and into a common header 20. In its preferred form, the header comprises a small casing of slightly greater width than the heating elements and extending substantially the entire length of the heater and communicates at one end thereof with any suitable form of pyrophoric or other type of lighting device 21. It will be apparent that when gas is admitted from the line 7 into the various Bunsen burner tubes the heat radiating elements will be filled with a combustible mixture. This mixture will, in turn, fill the header 20 so that upon operating the lighting device 21, a spark will be projected thereinto and the gas within the several heating elements ignited simultaneously. The open front of the heater may be provided with suitable guards 22 as is customary in stoves of this construction.

The advantages resulting from a gas heater constructed in accordance with the present invention arise from the facility of supporting the various heating elements in position within a common header, which

header forms means for simultaneously igniting the gas within each of the heating elements.

I claim:

- 5 1. A heater of the class described, comprising a casing, a supply line coöperating therewith, a series of independent heating elements operatively connected to said supply line and extending within the casing, a 10 header into which a portion of each of the heating elements extend, said header receiving a combustible mixture through said heating elements, and means coöperating with the header for simultaneously igniting 15 the gas in each of the heating elements, substantially as described.

2. A gas heater of the class described, comprising a portable supporting base, a gas supply line carried thereby, a casing supported on said base, a header formed in said casing, and a series of independent heating elements within said casing and communicating at opposite ends with said supply line and said header respectively for receiving gas from said supply line and feeding the same to said header for filling the header with an ignitable charge, said header having a width only slightly greater than the width of the heating elements and open-

ing at one end through the casing to facilitate igniting the charge therein, substantially as described.

3. In a heater of the class described, a supporting casing, a supply line coöperating therewith, a series of independent heating elements receiving gas from said line, a common header coöperating with the upper ends of said heating elements, said heating elements having openings formed in said ends for permitting the escape of gas 40 into said header, and a pyrophoric lighting device coöperating with one end of said header for simultaneously igniting the gas in all of said elements.

4. A gas heater, comprising a casing, a 45 plurality of hollow heating elements supported therein, means for supplying gas to the lower ends of said elements, a common header engaging the upper ends of said elements for receiving gas therefrom, said 50 header opening through one side of the casing to permit igniting the charge therein, and igniting means carried by the casing in cooperative relation to said opening, substantially as described.

In testimony whereof, I have hereunto set my hand.

WILLIAM D. ANTRIM.
